UNITED STATES PATENT OFFICE.

ROBERT C. PLAGGMIER, OF TAYLOR, NORTH DAKOTA, ASSIGNOR TO NATIONAL SUR-VAULT COMPANY, OF BISMARCK, NORTH DAKOTA, A CORPORATION.

BURIAL VAULT.

Application filed November 30, 1927. Serial No. 236,690.

This invention relates to burial vaults and particularly to that type of burial vault having therein a sealed casket chamber and a sealed dead air chamber above the casket 5 chamber for insulating the same.

It is the object of this invention to provide a new and improved seal in such a burial vault construction for the dead air insulating chamber.

10 This and other objects and advantages of the present invention will more fully appear from the following description made in connection with the accompanying drawings, wherein like reference characters refer 15 to the same or similar parts throughout the various views, and in which,

Fig. 1 is a view taken chiefly in vertical section of the vault longitudinally thereof on the line 1—1 of Fig. 2;

20 Fig. 2 is a vertical transverse section of the vault taken on line 2—2 of Fig. 1, and

Fig. 3 is a view on an enlarged scale illustrating one corner of the vault as viewed in Fig. 1.

25 Referring to the drawings, a substantially rectangular box 4 is provided, molded preferably from reinforced concrete and including a bottom and side and end walls, the top of the box being open. The side and

30 end walls of the box project straight upwardly from the bottom of the box for some little distance and are then slightly outwardly offset to form a continuous inwardly and upwardly projecting lower shoulder 5, whereupon the side and end walls again project straight upwardly for some little distance and are then again slightly outwardly offset to form an upper inwardly and upwardly projecting shoulder 6, whereupon the

40 walls are again extended vertically upwardly for a short distance and the upper ends of the walls are downwardly and inwardly beveled to form the beveled top edges 7. Above the upper shoulder 6, spiral reinforcements 8 are provided which are molded into the side and end walls and project inwardly therefrom. Preferably three or more of the reinforcements 8 are provided on each of the end walls at spaced intervals thereon,

45 while two reinforcements 8 are provided on each of the side walls one adjacent each end thereof.

50 In use for a burial the box will be situated within a grave such as the grave 9 so that the upper edges 7 of the side and end

walls will extend slightly above the level of the surface of the ground as indicated in the drawings or flush therewith. The box is then ready for the reception of a casket such as the casket 10. The casket is 60 lowered into the box so that the same rests on the bottom thereof. Slabs 11 are then lowered into the box and are of such size that they will fit and rest on the lower shoulder 5 to close the box above the casket 65 and to provide a casket chamber 12 defined by the bottom of the box, the portions of the side and end walls of the box between the bottom and the shoulder 5 and the bottom of the slabs 11. A layer 13 of molten concrete is then poured over the slabs 11 to completely cover the same and to provide an air tight and moisture proof seal for the casket chamber 12. Slabs 14 corresponding 70 to the slabs 11 are then placed within the box to fit therein and rest upon the upper shoulder 6 and provide a dead air insulating chamber 15 defined by the top of the layer of concrete 13, the side and end walls of the box between the layer 13 and the slabs 75 14, and the bottoms of the slabs 14. The slabs 14 fit below reinforcements 8 and are inserted in the box by being slid outwardly from the center of the box beneath the various reinforcements 8. Above the upper slabs 80 14, an upper layer 16 of molten concrete is placed, the said concrete completely covering the slabs 14 and being of sufficient depth to cover the reinforcements 8 and to extend even with or slightly above the inner sides 85 of the beveled upper edges 7. While the layer of concrete 16 is still in soft condition a cover slab 17 is placed over the top of the box to close the same. Cover slab 17 is provided with downwardly and inwardly 90 beveled end and side edges which fit against the beveled top edges 7 and are secured thereto by part of the cement formed in the layer 16. The bottom of the slab 16 is provided with a series of downwardly projecting spiral reinforcements 18 at spaced 95 points thereon and the said reinforcements are adapted to project into the soft concrete layer 16 and to bind the cover slab to the concrete. The bottom of the cover slab 100 17 will rest directly on the concrete layer 16. The cover slab may be finished off in an attractive design and will preferably be provided with a projecting headstone portion 19. The various surfaces formed on the top of 105 110

the slab 17 will all be slightly downwardly and outwardly beveled so that the cover slab will provide drainage surfaces at all points. Also the side and end edges of the cover 5 slab will project slightly beyond the outer top and side edges of the box 4 so that drainage of water from the top of the cover will take place outwardly from the sides and ends of the box.

10 With the present construction above the dead air chamber 15, an air tight and water proof seal is provided which will last indefinitely and will not be broken due to heaving of the ground from frost or other causes.

15 Pressure exerted against the outer side and end walls of a box 4 adjacent the level of the ground will be applied directly against the slabs 14, concrete layer 16 and the cover slab 17. The said parts will all be effectively 20 bound together and to the side and end walls of the box by means of the layer 16 and the reinforcements 8 and 18. A very rigid and heavy structure will thus be produced. The vault being closed at its upper end by the 25 top slab 17, layer 16 and the slabs 14, there will be a heavy absorbing surface provided which will absorb the heat from the outer air to prevent the dead air chamber 15 from being effected thereby. The dead air chamber 15 will form an additional insulation between the casket chamber and the outside air. Accordingly, the casket cannot 30 possibly be affected by outer air conditions and the corpse in the casket will keep indefinitely. When the box 4 is molded, iron 35 forms are preferably used which will afford a concrete surface impervious to air and water.

It will, of course, be understood that various changes may be made in the form, details, arrangement and proportions of the various parts without departing from the scope of the present invention, which, generally stated, consists in the matter shown and 40 described and set forth in the appended claims.

What is claimed is:

1. A burial vault having in combination,

a box adapted to extend into the ground and 50 have its top surface adjacent the surface of the ground, and having a casket chamber in its lower portion, a dead air chamber above said casket chamber and sealed therefrom, supporting means in said box at the top of 55 said dead air chamber, formed members resting on said supporting means and closing the top of said dead air chamber, a poured layer of concrete on said formed members and sealing the top of said dead air chamber, 60 and a formed cover slab resting on the top of said box projecting downwardly somewhat therein and having members embedded therein which are also embedded in said poured layer, whereby an air-tight and 65 moisture proof seal will be provided at the top of said dead air chamber and a heavy rigid construction provided at the top of said box.

2. A burial vault having in combination, 70 a box adapted to extend into the ground and have its top surface adjacent the surface of the ground, and having a casket chamber in its lower portion, a dead air chamber above said casket chamber and sealed therefrom, supporting means in said box at the 75 top of said dead air chamber, formed members resting on said supporting means and closing the top of said dead air chamber, a poured layer of concrete on said formed members and sealing the top of said dead air chamber, reinforcing means secured in and projecting inwardly from the walls of 80 said box and secured in said poured layer, a heavy cover slab resting on top of said box and said poured layer having reinforcing means in the bottom thereof extending into 85 said poured layer and said layer being set with the same therein, whereby said poured layer is bound to said box and to said cover slab and an air tight and moisture proof seal is provided at the top of said dead air chamber and a heavy rigid construction provided at the top of said box.

In testimony whereof I affix my signature.

ROBERT C. PLAGGMIER.
